UNITED STATES PATENT OFFICE.

AUGUST HOEHL, OF HALEDON, NEW JERSEY.

ELECTRIC SIGN.

1,077,532.

Specification of Letters Patent.

Patented Nov. 4, 1913.

Application filed November 23, 1912. Serial No. 733,125.

To all whom it may concern:

Be it known that I, AUGUST HOEHL, a citizen of the United States, residing at Haledon, in the county of Passaic and State of New Jersey, have invented certain new and useful Improvements in Electric Signs, of which the following is a specification.

This invention comprehends certain new and useful improvements in illuminated signs and relates more particularly to signs of this nature which are provided with removable perforated plates through which a light is adapted to shine.

The primary object of the invention resides in the provision of a sign of this type, which will be of extremely simple construction, cheap to manufacture, and which shall be particularly adapted for use at places of amusement.

A further and more specific object of the invention resides in the provision of a sign including a frame adapted to removably hold perforated plates, and colored plates, and a novel form of sheet-metal box encircling said frame.

With these and other objects in view, as will become more apparent as the description proceeds, the invention consists in certain novel features of construction, combination and arrangement of parts, as will be hereinafter fully described and claimed.

For a complete understanding of my invention, reference is to be had to the following description and accompanying drawings, in which,

Figure 1 is a front elevation of my improved sign, Fig. 2 is a vertical sectional view through the same, Fig. 3 is a transverse sectional view showing the sheet-metal box partly broken away, and, Fig. 4 is a detail view of one of the colored glass plates.

Referring to the drawings by numerals, 1 designates transverse bars and 2 designates upright bars, which in conjunction with the first mentioned bars, form a frame. These bars are preferably made of hard wood and cross bars 1 are provided along their upper and lower sides with a plurality of longitudinal grooves adapted to receive and hold suitably perforated plates 3 and colored glass plates 4. The upright bars 2 are provided with longitudinal slots 2' extending entirely therethrough for the purpose of receiving the ends of said plates.

As shown in Fig. 1, the perforated plates

3 may carry any desired characters and the plates 4, which are preferably made of glass, may be colored in any manner desired. In Fig. 4 I have shown one of these plates 4 colored red, white and blue so that the words "National Theater" will appear in three colors. It is to be understood that this is only one of the various ways in which I may have the plates colored.

In order to provide a backing for the hard wood frame, I employ a sheet-metal case or box having a concave or convex rear wall 5, a downwardly and rearwardly inclined top wall 6, side walls 7, 7', and a rearwardly and upwardly inclined bottom wall 8. The forward edge of the top wall 6 overlies the uppermost transverse bar 1 and has its extremity bent upwardly, as indicated at 9. The side wall 7 is bent outwardly, as at 10, forwardly as at 11, and then inwardly, as at 12, thus forming a channel for the reception of the vertical frame bars 2. The side wall 7' is bent laterally, as at 13, for engagement with the transverse frame bars 1. The bottom wall 8 of the casing extends under the lowermost transverse bar 1 and is then bent upwardly. This structure provides a projecting means for the frame and prevents it becoming worn from contact with its supporting surface. A sheet-metal strip 14 extends transversely of the frame bars 1 and is opposed to the lateral projected portion 13 of the side wall 7'. If desired, an ornamental head piece 15 may be secured to the top of the frame. It will be apparent that this construction permits of the ready insertion and removal of the plates 3 and 4, and that the portion 11 of the wall 7 limits the movement of said plates in one direction, thus making it easy to properly position them within the frame. Any number of lights 16 may be secured to the rear wall 5 of the sheet-metal box for the purpose of making the advertising matter carried by the perforated plates 3 clearly readable at night. In order to adjustably support the sign in an essentially vertical position, I provide the rearwardly projecting apertured arm 17 through which a pointed rod 18 is adapted to slide, said rod being held in any adjusted position by the set screw 19.

It is to be understood that while I have shown and described the preferred embodiment of my invention, I do not wish to be limited to this exact construction and ar-

rangement of parts, but may make such changes as may fall within the scope and spirit of the appended claims.

Having thus described my invention, what

5 I claim is:—

1. In a sign of the character described, a pair of longitudinal bars, transverse bars connecting said longitudinal bars, thereby forming a frame, the first mentioned bars 10 being provided with longitudinal slots extending therethrough, the second mentioned bars being provided with longitudinal grooves communicating with said slots, a casing formed from a single piece of material and comprising a rear wall, top and bottom walls and side walls, one of said side walls being bent laterally, forwardly and inwardly to provide a channel for the reception of one side of said frame, thereby closing 15 the outer sides of the longitudinal slots in said side, the other side wall being bent laterally for engagement with the frame, the bottom wall being extended along the

lowermost transverse bar and then upwardly, and a plurality of plates adapted 25 to be held within said slots and grooves.

2. A sign of the character described, comprising a frame having longitudinally grooved transverse bars, a casing supporting said frame, said casing including a rear 30 wall, top and bottom walls, and side walls, one of said side walls being bent to form a channel for the reception of one side of said frame, the other side wall being bent laterally for engagement with the frame, the 35 bottom wall of said casing being extended under the frame and then upwardly, and suitable lighting means carried on the inner side of the rear wall of said casing.

In testimony whereof I affix my signature 40 in presence of two witnesses.

AUGUST HOEHL.
